SYRINGE OR APPLICATOR

Herman B. Lermer, Newark, N. J., assignor, by
mesne assignments, to Hygienic Tube & Con-
tainer Corporation, Newark, N. J., a corpora-
tion of New Jersey

Application October 14, 1936, Serial No. 105,508

1 Claim. (Cl. 128—230)

This invention relates to improvements in de-
vices for applying medicaments to orifices of the
body.

Heretofore there have been provided medica-
ment applicators comprising a tube having a pis-
ton slideable therein. It has been found that the
piston has a tendency to "stick" or "freeze" in
one end of the tube and thus prevents an easy ap-
plication of the medicament.

10 It is an object of this invention to provide a
medicament applicator comprising a tube hav-
ing a piston slideably mounted therein, the piston
and other parts of the applicator being so con-
structed as to prevent or overcome freezing of the
15 piston and thereby facilitate the applying of
a medicament to orifices.

A further object of the invention is to provide
an applicator which can be readily and releas-
ably connected to a medicament container such
20 as is extensively used for merchandising medica-
ments and jellies for feminine hygiene.

These and other advantageous objects, which
will later appear, are accomplished by the sim-
25 ple and practical construction and arrange-
ments of parts hereinafter described and exhib-
ited in the accompanying drawing, forming part
hereof, and in which:

Fig. 1 is an elevational view of a medicament
applicator embodying my invention showing the
30 bulb detached,

Fig. 2 is a sectional view of the applicator
shown in Fig. 1 showing the bulb detached,

Fig. 3 is an elevational view of a modified form
35 of the invention showing the bulb-detached, and

Fig. 4 is a sectional view of the form shown in
Fig. 3 showing the bulb detached.

Referring to the drawing, in Figs. 1 and 2
there is shown a device for applying medicaments
40 to body orifices, comprising a tube 1 which is
preferably made of a flexible, transparent, non-
breakable material. However, the tube 1 can be
made of any suitable material, for noting the
contents thereof, if desired. Attached to one end
45 of the tube 1 is a bulbous tip 2 which has a pas-
sage 3 therein of less diameter than the internal
diameter of the tube 1; and has a shoulder 4 up-
on which rests the end of tube 1. The passage 3
is internally threaded at 5. Slidably mounted in
50 the tube 1 is a piston 6 having reduced portions
7 which are adapted to enter the passage 3.

The other end of the tube 1 is provided with a
bulbous tip 2 also having the structure above de-
scribed.

In operation, the tube can be loaded at either
55 end with a medicament by screwing the bulbous

tip onto the medicament container, which will
force the piston to the other end of the tube. In
many instances, the piston has a tendency to stick
upon the shoulder 4 of the tip and thereby pre-
5 vent discharge of the medicament when desired.
In order to overcome the sticking or freezing of
the piston on the shoulder 4, a connector 8 hav-
ing a threaded portion 9 adapted to engage the
thread 5 of the tip, is provided with a conical ex-
10 tension 10 which engages the reduced portion 7 10
of the piston 6 and forces the latter off of the
shoulder 4. The connector 8 is provided with a
passage 11 which communicates with the rubber
bulb 12 by means of which pressure is applied to
the piston to discharge the medicament from 15
the tube.

From the above description it will be seen that I
provide an applicator which has each end thereof
adapted for connection to a medicament contain-
er or to a connector 8 carrying a bulb.

By means of my arrangement, all tendency of
the piston to stick or freeze is overcome.

In Figs. 3 and 4 is shown a modified form of
the invention in which a tube 20 is provided with
a bulbous tip 21 having a shoulder 23 receiving
25 one end of the tube 20, said tip having a passage
24 of less diameter than the internal diameter of
the tube 20 and accommodating the reduced por-
tion 25 of a piston 26.

The passage 24 is internally threaded at 27 so 30
that it can be releasably connected to a medica-
ment container.

Attached to the other end of the tube 20 is a
head 28 having a shoulder 29 upon which the
end of the tube rests. The head 28 is provided
35 with a conical passage 30 adapted to receive the
reduced portion 25 of the piston 26.

The piston is forced in one direction in the
tube by means of pressure derived from a rubber
bulb 31 which is attached to a connector 32, the 40
latter having a conical portion 33 projecting into
the conical passage 30 of the head 28. The
conical portion 33 is of such a length that when
forced into the passage 30, it will engage the re-
duced portion 25 of the piston and force the pis-
ton off of the shoulder 29. By means of this
structure all tendency of the piston to freeze or
stick on the shoulder 29 is overcome.

The foregoing disclosure is to be regarded as
descriptive and illustrative only, and not as re-
strictive or limitative of the invention, of which
obviously an embodiment may be constructed,
including many modifications, without departing
from the spirit and scope of the invention, set
forth in the appended claim.

Having thus described my invention, what I claim as new and desire to secure by Letters Patent, is:

In a device of the class described, a tube; a member attached to one end of said tube, said member having an internal shoulder engaging the end of the tube, and a conical passage of less diameter than the tube, a piston slidably mounted in the tube and having a reduced portion adapted to move into said conical passage when

the piston rests upon said internal shoulder, and a bulb for moving the piston in the tube, said bulb being attached to a connector having a conical tip adapted to be received by the conical passage in said member, said conical tip being of sufficient length to engage the reduced portion of the piston and move the piston off of the internal shoulder. 5

HERMAN B. LERMER.
